UNITED STATES PATENT OFFICE.

ALBEN E. LUNDELL, OF NEW YORK, N. Y., AND FRANKLIN A. STEARN, OF PATERSON, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

1,330,483.

Specification of Letters Patent. Patented Feb. 10, 1920.

Application filed October 8, 1917. Serial No. 195,356.

To all whom it may concern:

Be it known that we, ALBEN E. LUNDELL and FRANKLIN A. STEARN, citizens of the United States, residing at New York, in the 5 county of Bronx and State of New York, and at Paterson, in the county of Passaic and State of New Jersey, respectively, have invented certain new and useful Improvements in Telephone-Exchange Systems, of 10 which the following is a full, clear, concise, and exact description.

This invention relates to telephone exchange systems, and more particularly to 15 improvements in systems employing machine switching.

The object of this invention is to provide means for continuing the hunt for an idle 20 trunk if all the trunks of a group normally associated with a selector switch are busy at the time that the hunting operation takes place.

According to a feature of this invention the hunting selector switch after having passed over all the trunks leading directly 25 to selector switches for the further extension of a line, passes to an idle overflow trunk. Associated with each of these overflow trunks there is a rotatable switch which is capable of hunting over an equivalent group 30 of trunks continuously until an idle trunk is found.

In the drawings, Figure 1 represents a calling subscriber's line, an operator's connecting circuit and a selector switch; Fig. 2 35 (to be placed to the right of Fig. 1) a sequence switch arranged to seize an idle connector switch to extend a call to a called subscriber's line; and Fig. 3 (to be placed below Fig. 1) an operator's controlling apparatus 40 by means of which the selector and connector switches may be set.

The selector and sequence switches and the controlling apparatus therefor will not be disclosed in full in the following description 45 of this system, switches of this type being well-known in the art. A complete description of such switches may be had from a Patent No. 1,168,319, patented January 8, 1916, to A. E. Lundell.

50 The calling subscriber at station 100, desiring to obtain a connection with a subscriber at station 200, removes his receiver from the switchhook, closing thus a circuit for line relay LR, which lights a calling sig-

nal lamp CL. The operator, noticing lamp 55 CL lighted, inserts a plug 101 into a jack 102 in which the calling line terminates, whereupon a circuit is closed from grounded battery through the winding of cut-off relay CR, the sleeve contacts of jack 102 and 60 plug 101, and the winding of a relay 103 to ground. Relay 103 closes a circuit from ground through its armature and front contact, a contact 104 and the power magnet of a sequence switch 105 to grounded battery. 65 Under the control of a normal spring 106, sequence switch 105 is moved out of position 1 into position 2. A circuit is now closed from ground through sequence switch contact 107, conductor 108, a contact 300 70 of a sequence switch 301, and the winding of a relay 302 to grounded battery. Relay 302 becomes energized and closes a circuit from ground through its left-hand armature and front contact, a contact 303 and the power 75 magnet of the sequence switch 301 to grounded battery. Under the control of a normal spring 304, sequence switch 301 is moved out of position 1 into position 3. Relay 302 does not become deenergized when 80 sequence switch 301 leaves position 1, a circuit being closed from grounded battery through the winding of this relay, sequence switch contact 305, the right-hand armature and front contact of relay 302, conductor 85 306 and contact 109 of sequence switch 105, to ground.

The operator by depressing her listening key 110, connects her telephone set 111 into telephonic association with the calling subscriber, and, in accordance with instructions received from the subscriber, she adjusts her controlling apparatus. Only two rows of keys are shown in Fig. 3, as it is thought sufficient for the purpose of the 95 present invention. It will be obvious to those skilled in the art that the switches used will be set in accordance with a plurality of digits in order to extend the calling line toward the called line and that for 100 this purpose a plurality of rows of keys must be provided at the operator's position. Supposing, however, that the called subscriber's line may be seized by causing selector switch 130 to take three steps, the operator will depress key 310 and similar keys 105 for controlling connector switches and a start-key 312. A circuit is established from

ground through the contact of key 312, a contact 313, and the power magnet of sequence switch 301 to grounded battery, for moving this sequence switch into position 4. 5 A circuit is then closed from grounded battery through the winding of relay 113, sequence switch contact 114, conductor 115, the outer armature and back contact of the upper counting relay O, the winding of a 10 stepping relay 315, sequence switch contact 314, conductor 316, and a sequence switch contact 116 to ground. Relays 113 and 315 become energized. Relay 113 closes a circuit from ground through its right-hand armature and front contact, a sequence switch contact 117, conductor 118, and the power magnet of the sequence switch 105 to grounded battery, for moving this sequence switch into position 3. Relay 113 remains 15 energized upon the opening of contact 114, due to the closure of a substitute path through the left-hand armature and front contact of this relay, and a sequence switch contact 119. 20 Upon the energization of relay 315, a circuit is closed from ground through the front contact and armature of this relay, a sequence switch contact 317, conductor 318, the contact of the key 310, conductor 322, the armature and back contact of the upper counting relay 2 and the winding of the lower counting relay 2 to grounded battery. The lower counting relay 2 closes a circuit from ground through sequence switch contact 320, conductor 321, the armature and front contact of the lower counting relay 2, and the windings of the upper and lower counting relays 2 to grounded battery. The upper counting relay 2, however, can not become energized 25 due to the closure of a short circuit around its winding from ground through sequence switch contact 317, to ground through the armature and front contact of stepping relay 315. 30 In position 3 of sequence switch 105, a circuit is closed from grounded battery through the winding of a driving magnet 120, a sequence switch contact 121, and the right-hand front contact and armature of relay 113 to ground. Magnet 120 attracts 35 its armature 122 and presses thus a brush rod 123 against a roller 147 constantly rotating in the direction indicated by the arrow. The brush rod with selector wipers 124, 125, 126 and commutator brushes 127, 128 is moved in an upward direction, the wipers 124, 125, 126 wiping over a terminal bank 129 and the commutator brushes 127, 128 over conducting and insulated segments 40 of a commutator plate 112. When the commutator brush 128 engages a conducting segment 131, it connects ground through this segment, a conductor 132, sequence switch contact 133 and 119 to relay 113, thus 45 shunting out relay 315. Relay 315 opens at

its front contact the short circuit of the upper counting relay 2, whereupon this counting relay becomes energized and connects conductor 322, through its armature and front contact, the armature and back contact 70 of the upper counting relay 1, the winding of the lower counting relay 1, and conductor 323, to grounded battery. The lower counting relay 1 connects now the upper counting relay 1 into circuit. This relay, 75 however, can not become energized due to the fact that commutator brush 128 moved in the meantime into engagement with an insulated segment 134, permitting thus the reenergization of relay 315, which again connects ground to conductor 322. 80

The operation of the counting relays continues in substantially the same manner until the selector 130 has been moved upward by three steps and the upper counting 85 relay O has become energized. This counting relay opens, at its outer armature, the fundamental circuit including relays 315 and 113, and closes a circuit from ground through sequence switch contact 324, the 90 inner armature and front contact of the upper counting relay O and the power magnet of sequence switch 301 to grounded battery, for moving this sequence switch into position 6. When the sequence switch leaves 95 position 4, all the counting relays which have been locked up become deenergized.

Relay 113, upon deenergization, opens the circuit of magnet 120 and closes a circuit from ground, through its right-hand armature and back contact, sequence switch contact 135, conductor 118, and the power magnet of sequence switch 105 to grounded battery, for moving this sequence switch out of position 3 and into position 6. 100 105

A circuit is now closed from ground through sequence switch contacts 136 and 137, and the left-hand winding of a relay 138, to grounded battery.

The energization of relay 138 closes a circuit from ground, outer right-hand armature and front contact of this relay, sequence switch contact 140, conductor 118 and the power magnet of sequence switch 105 to grounded battery, whereupon the sequence 110 switch will be moved into position 7. When the sequence switch 105 leaves position 6, the circuit above traced for relay 138 is opened at contact 136, but this relay remains energized due to the closure of a circuit from 115 grounded battery, right-hand winding of relay 138, inner right-hand armature and front contact of this relay, conductor 152, brush 126, to ground over the test conductor of the trunk with which brush 126 is in engagement, provided this trunk is busy. In 120 position 7 a circuit is completed for updrive magnet 120, if relay 138 is energized, from ground, battery, winding of the magnet, contact 145, outer armature and front contact 125 130

of relay 138 to ground, thus causing the movement of the selector onto the terminals of another trunk.

Let us suppose that all the trunk lines 5 extending direct to final selector switches in the third group of contacts of the bank 129 are busy, that is to say, ground is to be found on the test contacts 139 and the multiple terminals thereof, we will also assume 10 that the first overflow trunk at the top of this group of trunks is idle; that is, no ground will be on its test terminal.

Therefore as soon as test brush 126 engages the test terminal 139 of the idle 15 overflow trunk and the commutator brush 127 engages an insulated segment 141, relay 138 becomes deenergized and opens the circuit of magnet 120, thus arresting the brush rod 123. Relay 138 closes a circuit 20 from ground through its outer right-hand armature and back contact, sequence switch contact 146, conductor 118 and the power magnet of sequence switch 105 to grounded battery for driving this sequence switch 25 into position 11.

In position 11 of sequence switch 105, a circuit is completed from ground, contact 116, conductor 316, contact 151, brush 125, conductor 203, lower armature and back 30 contact of relay 205, left-hand armature and back contact of relay 206, left-hand winding of relay 207 to grounded battery. Relay 207 completes circuit from grounded battery, winding of relay 208, right-hand 35 armature and back contact of relay 206, left-hand armature and front contact of relay 207 to ground. Relay 208 completes a locking circuit for itself from grounded battery, winding of relay 208, inner left-hand armature and front contact of this 40 relay, conductor 209, terminal 139, brush 126, conductor 152, inner right-hand armature and back contact of relay 138, contact 153 to ground. Relay 208 closes a circuit 45 from grounded battery, winding of relay 206, outer left-hand armature and front contact of relay 208, lower armature and back contact of relay 205 to ground over conductor 203.

50 The sequence switch 225 does not have a definite normal position, but remains in engagement with the last trunk to which it extended a call. When this trunk becomes idle and is later seized by a selector switch 55 similar to 130, ground will be placed upon the test wire 211 through contact similar to 153 at this selector switch. Therefore when relays 208 and 207 become energized in the manner above described a locking circuit 60 for relay 207 is completed from grounded battery right-hand winding and right armature and front contact of this relay, outer right-hand armature and front contact of relay 208, contact 1, 2, 3, 4, 5, 6, 7 65 or 8 of sequence switch 225, test conductor

211 to ground. This locking circuit prevents the deenergization of relay 207 when relay 206 becomes energized in the manner above described. Relay 206 therefore completes a circuit from grounded battery, 70 winding of power magnet of sequence switch 225, right-hand armature and front contact of relay 206, left-hand armature and front contact of relay 207 to ground.

This circuit causes the sequence switch to 75 move into its next position wherein the above operation will again be performed, provided the trunk there encountered is busy. While the sequence switch is moving from one position to the next, a circuit 80 is completed through the left-hand winding of relay 207 in order to maintain this relay energized. This may be traced from grounded battery left-hand winding of relay 207, left-hand armature and front contact 85 of relay 206, contact 214, left hand armature and front contact of relay 207 to ground.

We will assume that when the sequence switch 225 reaches the seventh position, it 90 finds an idle trunk. The circuit through the right-hand winding of relay 207 will then be opened, since no ground will be found upon the test conductor 211. Relay 207 therefore deenergizes and opens the circuit 95 for the motor magnet of the sequence switch. Relay 207 also closes a circuit from grounded battery, winding of relay 205, inner right-hand armature and front contact of relay 208, left-hand armature and back 100 contact of relay 207 to ground.

Relay 205 opens the circuit of relay 206 and extends the conductors 202 and 203 through to the connector switch associated with the selected idle trunk. Relay 205 105 also by attracting its upper armature completes the fundamental circuit through to the stepping relay (not shown) at the connector switch. This stepping relay will be controlled in the well known manner to 110 operate the connector to complete the connection to the called subscriber substation 200. Since this operation does not form part of this invention, it is believed that a 115 complete description of the operation is unnecessary.

The subscribers desiring disconnection restore their receivers to the switchhooks, causing thus, in the well-known manner, the actuation of supervisory signals 160 and 161. 120 The operator noticing the actuation of these signals removes plug from jack 102, whereupon relays CR and 103 become deenergized, the latter closing a circuit from ground through its armature and back contact, and 125 a contact 162 and the power magnet of sequence switch 105 to grounded battery, whereupon this sequence switch is moved into position 18. In position 18 of the sequence switch, a circuit is closed from 130

grounded battery, through the winding of magnet 163 and a sequence switch contact 164 to ground. Magnet 163 presses, by means of its armature 165, the brush rod 123 5 against a roller 166 constantly rotating in the direction indicated by the arrow, and the brush rod with the wipers and brushes mounted thereon is lowered. When the brush rod reaches its normal position, a circuit is closed 10 from ground, through commutator brush 128, a conducting segment 167, conductor 168, a contact 169, conductor 118, and the power magnet of sequence switch 105 to grounded battery, for moving this sequence 15 switch out of position 18 into position 1. When the sequence switch leaves position 18, magnet 163 becomes deenergized.

As soon as sequence switch 105 leaves position 16, the contact 153 is opened, causing 20 the deenergization of relay 208, which in turn opens the circuit of relay 205.

Relay 208 removes ground from test conductor 211, thus causing the release of the connector switch in the well known manner.

25 If the sequence switch 225 had been in position 7 at the time the overflow trunk was seized by the selector 130 no ground would have been found upon the test wire 211 for completing the locking circuit of relay 207 30 through its right-hand winding and armature and therefore when the relay 206 is energized in the manner above described the relay 207 deenergizes, since contact 214 is open in position 7. Relay 207 is so constructed that it will release its armatures before the circuit of the power magnet of sequence switch 225 is completed through the front contact of relay 206. The sequence 35 switch will therefore remain in position 7.

40 What is claimed is:

1. In an automatic telephone system, incoming lines, groups of trunks, overflow trunks associated with each group of trunks, a hunting switch associated with each overflow trunk, a group of trunks terminating at each of said switches, said switches being arranged to be normally in engagement with any one of the said last mentioned trunks terminating thereat, means for connecting 45 an incoming line to an overflow trunk, means actuated by said connection for operating the switch associated with said overflow trunk to extend the connection to the trunk with which it is in engagement if said trunk 50 is idle or to start hunting for an idle trunk if said trunk is busy, and means for stopping

said switch upon the first idle trunk engaged.

2. In an automatic telephone system, incoming lines, groups of trunks, overflow trunks associated with each group of trunks, a hunting switch associated with each overflow trunk, said switches having no definite normal positions, a group of trunks terminating at each of said switches, means for connecting an incoming line to an overflow trunk, means actuated by said connection for operating the switch associated with said overflow trunk to extend the incoming line 60 to an idle trunk.

3. In an automatic telephone system, incoming lines, groups of trunks, overflow trunks associated with each group of trunks, a hunting switch associated with each overflow trunk, a group of trunks terminating at each of said switches, each of said switches having no definite normal positions and being arranged to be normally in engagement with any one of the trunks terminating 75 thereat, means for connecting an incoming line to an overflow trunk, means actuated by said connection for operating the switch associated with said overflow trunk to extend the connection to the trunk with which it is 80 in engagement if said trunk is idle or to start hunting for an idle trunk if said trunk is busy, and means for stopping said switches upon the first idle trunk engaged.

4. In a telephone system, a line, a selective switch for extending said line, groups of trunks terminating in said switch, overflow trunks associated with each said group, means for selectively setting said switch in association with any of said groups, means 85 responsive to the busy condition of all trunks constituting said selected group for setting said switch on an idle one of said overflow trunks, an equivalent group of 90 trunks associated with each overflow trunk, a unidirectional rotatable selective switch having no normal position for automatically extending said overflow trunk to an idle trunk in said equivalent group, and means 95 responsive to the extension of said line to 100 said overflow trunk for causing the actuation of said unidirectional rotatable switch.

105 In witness whereof we hereunto subscribe our names this 1st day of October, A. D. 1917.

ALBEN E. LUNDELL.
FRANKLIN A. STEARN.
